[57] CLAIM

The ornamental design for a jewelry rack, as shown and described.

DESCRIPTION

FIG. 1 is a top, front and right side perspective view of a jewelry rack showing our new design;
FIG. 2 is a rear elevational view thereof;
FIG. 3 is a top plan view thereof;
FIG. 4 is a bottom plan view thereof;
FIG. 5 is a right side elevational view thereof, the left side being a mirror image of that shown;
FIG. 6 is a top, front, and right side perspective view of a second embodiment thereof;
FIG. 7 is a rear elevational view of the embodiment of FIG. 6;
FIG. 8 is a top plan view of the embodiment of FIG. 6;
FIG. 9 is a bottom plan view of the embodiment of FIG. 6; and,
FIG. 10 is a right side elevational view of the embodiment of FIG. 6, the left side being a mirror image of that shown.

FIG. 1
